AIR PISTOL

Franz Möller, Zella-Mehlis, Germany

Application February 1, 1937, Serial No. 123,539
In Germany January 31, 1936

12 Claims. (Cl. 124—15)

(Granted under the provisions of sec. 14, act of
March 2, 1927; 357 O. G. 5)

This invention relates to air weapons, more particularly air pistols, and refers in particular to improvements relating to the cocking and trigger mechanism of weapons of this nature.

Owing to the desire to furnish the weapon with the usual pistol form the cocking lever in the known air pistols having a fixed air cylinder and a drop barrel is merely short, so that a very short lever arm results and considerable force is required to cock the weapon. In view of the exertion associated with the cocking of weapons of this nature the person employing the weapon quickly tires and acquires an unsteady hand.

To avoid the disadvantages of the known weapon the cocking lever in accordance with the invention is constructed with two arms and covers with its longer arm, which forms the grip or handle of the lever, the rear portion of the barrel and the air cylinder, while the shorter arm, which is constructed as discharge member, engages below the barrel and is connected there to the cocking rod. In this embodiment of the invention the trigger mechanism is disposed, for example, below the cocking lever for the purpose of attaining as compared with the known air weapons having the trigger rod, disposed behind the cocking rod a shorter length and accordingly an improved usefulness of the weapon. The air weapon according to the invention combines maximum output, ready cocking, good balance in the hand, long line of sight identical with the position of the barrel with short overall length of the weapon, and minimum cost of production.

In order in this embodiment according to the invention also to obtain a small height, and accordingly to move the trigger mechanism and the grip nearer towards the centre line of the air cylinder, the cocking rod actuated by the cocking lever is, in accordance with an additional embodiment of the invention, constructed in bifurcated form and the trigger mechanism is disposed between the fork of the cocking rod.

The telescopic arrangement of the parts may naturally also be performed in other suitable fashion. The arrangement according to the invention corresponding to the embodiment concerned also permits of the provision, with simple means, of the safety device for the trigger, which prevents the weapon from being discharged in the opened condition.

Additional features of the invention will become apparent from the following description and the accompanying drawings.

In the drawings there are shown two forms of

embodiment of the air weapon according to the invention,

Fig. 1 showing the cocking lever according to the invention as applied to an air pistol shown in elevation.

Fig. 2 shows the same arrangement viewed from above.

Fig. 3 is a view of the cocking lever from the front, and

Fig. 4 shows the cocking lever in the opened position.

In these embodiments the trigger mechanism is disposed below the cocking rod actuated by the cocking lever constructed in accordance with the invention.

Fig. 5 shows, partially in section, an air pistol similar to that in Fig. 1, wherein the cocking rod actuated by the cocking lever is constructed in bifurcated form and the trigger mechanism is disposed between the fork of the cocking rod.

Fig. 6 is a cross-section taken through the air cylinder, the bifurcated cocking rod and the trigger mechanism.

Fig. 7 is a perspective view from below of the embodiment according to Fig. 5 showing the cocking and trigger mechanism partially from the side, and

Fig. 8 shows the cocking lever in the opened position corresponding to Fig. 4.

In the drawings the cocking lever according to the invention is designated 1 (1^a, 1^b, 1^c, 1^d), and in the form of embodiment shown it is constructed as a two-armed lever, which is mounted to rock about a pin 3 on both sides of the barrel 2. The pin 3 is carried by the supporting arm 4 (Figs. 3 and 4), which is integral with the air cylinder 5. Towards the front the short lever arms 1^c situated on either side unite with the cocking rod 6 to form a joint, which is situated below the barrel 2 and is connected by the pin 7. Towards the rear the two arms 1^c combine to form a grip 1^b, and this, covering the rear end of the barrel 2, bears against the air cylinder 5 and terminates in a sight formed at 1^d. To preclude accidental movement there are provided the projections 8 and the recesses 9.

The operation of the cocking lever is as follows:

If the cocking lever 1^a is gripped by the arm 1^b and lifted away from the pistol, it rocks about the pin 3. The rocking of the lever 1^a causes the pin 7 of the short lever arm 1^c to move towards the air cylinder 5 (compare Fig. 4). The cocking rod 6, which is pivotally secured to the arm 1^c by the pin 7, engages with its end 6^a through a

slot in the air cylinder 5, and with the assistance of a desired holding and trigger mechanism cocks the air piston in the known manner. These parts are not particularly shown in Figs. 1 to 4.

5 The closed cocking lever 1^a (Figs. 1, 2 and 3) covers at the point designated 1^a the rear end of the barrel 2 and thus holds the same in the closed position.

If the cocking lever 1 is rocked for the purpose 10 of cocking the weapon, the barrel 2, which is acted upon by the spring 10, is also rocked to a certain extent by the friction of the laterally resilient projections 8 on the lever 1 against the curvature of the barrel 2, and the small spring 15 10 holds the same open for charging purposes (see Fig. 4). When the cocking lever 1 is again closed it moves, by means of the part 1^a, the barrel 2, which preferably has the same fulcrum 3 as the cocking lever 1, and the cocking rod 6 20 into the position according to Fig. 1. The two laterally resilient projections 8 on the cocking lever 1 enter corresponding recesses 9 in the arm 4 of the air cylinder 5 and hold the cocking lever 1 and together therewith the barrel 2, which 25 bears in airtight fashion against the air cylinder, in the closed condition. The end 1^b of the cocking lever forms at the same time by reason of suitable construction the sight 1^d. In this way 30 there is obtained the long line of sight identical with the position of the barrel which is necessary for an air weapon of good design.

The embodiment illustrated in Figs. 5 to 8 shows a cocking lever in accordance with Figs. 1 to 4 also, by way of example, in conjunction 35 with an air pistol. In this embodiment, however, the cocking rod is constructed in bifurcated form and the trigger mechanism is disposed between the arms of this rod.

In the air cylinder 5 there is located the air 40 piston 11. The same is acted upon by the pressure spring 12. The air cylinder 5 is closed at the rear by the detachable cover 13 and at the front by the sleeve head 14, with which there is firmly connected the arm 4 (Fig. 8). This arm 4 serves 45 for attachment of the barrel 2 with the aid of the pin 3, and is adapted as regards its upper face to the cross-section of the barrel 2, whereby there is ensured absolute immovability of the barrel 2 when the pistol is closed. The pin 3 acts simultaneously as pivot for the cocking lever 1, which 50 is connected by the pin 7 to the cocking lever joint 15, this in turn being connected by the pin 16 to the bifurcated cocking rod 6 (6^a, 6^b). The bifurcated rod may consist equally well of two iron strips riveted together or of one single forked member. The cocking rod 6 is guided in the cocking rod guide 17, which is secured to the air cylinder 5 and in which there is mounted the trigger 19 with the aid of the pin 18. The trigger 19 carries the safety pin 20. The arms 6^a, 6^b of the rod 6 are widened out towards the front and are furnished at their rear ends with outwardly set off abutments 21 which, upon the cocking of the pistol, move the air piston 11 towards the rear 55 until it engages with the catch rod 22. The catch rod 22, with the assistance of the pin 23, is mounted to rock in the retaining member 24, which is firmly connected to the air cylinder 5 and serves simultaneously for attachment of the stock 25 with the assistance of the hook-shaped pin 26 and the nut 27. The trigger 19 and the catch rod 22 are acted upon by the pressure of the spring 28, and are provided between the arms 6^a, 6^b of the rod 6, as disclosed very clearly by Fig. 7. 70 75 In this figure, for the sake of more comprehensive

illustration, the guide 17 for the cocking rod and the retaining member 24 have not been particularly shown.

The operation of the weapon according to this form of embodiment is as follows:

For opening and cocking the pistol the cocking lever 1 is moved towards the front. In this way the barrel 2, which is acted upon by the spring 10, is exposed for charging purposes. At the same time, through the medium of the cocking lever 10 joint 15 and the bifurcated cocking rod 6 with its abutments 21, the piston 11 is moved back against the action of the spring 12 until it is engaged and held by the resilient catch rod 22. During the backward and forward movement of 15 the cocking rod 6 the trigger 19 cannot be pressed. The pistol, therefore, is secured. This is accomplished by the fact that a widened portion of the front part of the rod 6 prevents an upward movement of the safety pin 20 and accordingly 20 a movement of the trigger 19 towards the rear, so that the catch rod 22 cannot be released during the opening and cocking of the pistol. The free movability of the trigger 19 is shown in Fig. 5, the obstructed movement in Fig. 8. Upon the 25 closing of the pistol all parts return to the position in Fig. 5, while the piston 11 remains in the position shown in Fig. 8. By pressure on the trigger 19 the catch rod 22 is released, the air piston 11 jumps forward, and the missile is 30 forced through the barrel 2 under the action of the compressed air.

What I claim as new and desire to secure by Letters Patent is:

1. An air weapon comprising a barrel rotatable around a fixed point to permit the barrel to tilt, a stationary air cylinder having a piston therein and a compression spring for driving said piston when the spring is tensioned, a trigger mechanism, a cocking lever, a cocking rod connected at one end to the cocking lever and the other end cooperating with the piston, and a spring-urged catch rod having one end projecting into the air cylinder and in the path of the piston to hold said piston under the tension of said compression spring, and the other end contacting directly with the trigger, said cocking rod and catch rod telescoping relative to each other.

2. An air weapon comprising a barrel rotatable around a fixed point to permit the barrel to tilt, a stationary air cylinder having a piston therein and a compression spring for driving said piston when the spring is tensioned, a trigger mechanism, a cocking lever, a cocking rod connected at one end to the cocking lever and the other end cooperating with the piston, and a spring-urged catch rod having one end projecting into the air cylinder and in the path of the piston to hold said piston under the tension of said compression spring, and the other end contacting directly with the trigger, said cocking rod being forked and the catch rod being provided between the two arms of the fork to permit relative movement between these members.

3. An air weapon according to claim 2, in which the air cylinder is provided with two elongated slots in which the forks of the cocking rod are guided.

4. An air weapon according to claim 2, in which a guide is provided secured on the cylinder for guiding the cocking rod.

5. An air weapon according to claim 2, in which a guide is provided secured on the cylinder for

guiding the cocking rod, and in which a retaining member is provided secured to the air cylinder and which guides and pivots the catch rod.

6. An air weapon according to claim 1, in which a pin is provided on the trigger and the cocking rod having a widened portion which is adapted to contact the pin on the trigger during the cocking operation and to prevent release of the trigger until the catch rod has contacted the piston and the cocking lever has completed the cocking movement.

7. An air weapon comprising a barrel rotatable around a fixed point to permit the barrel to tilt, a stationary air cylinder having a piston therein and a compression spring for driving said piston when the spring is tensioned, a trigger, a cocking rod cooperating with the piston for moving the piston in its cylinder to tension the spring, a cocking lever consisting of two arms of unequal length in which the longer arm will contact and cover the rear portion of the barrel and the air cylinder and the shorter arm projects below the barrel and is pivotally connected to the cocking rod, and a catch rod having one end projecting into the air cylinder and in the path of the piston to hold said piston under the tension of the compression spring and the other end contacting directly with the trigger.

8. An air weapon according to claim 7, in which a spring is provided between the air cylinder and one end of the catch rod to urge the other end of the catch rod into the air cylinder and

to urge the trigger into the non-operative position.

9. An air weapon according to claim 7, in which means are provided for tilting the barrel, and the longer arm of the cocking lever where it covers the rear portion of the barrel being adapted to contact the barrel for maintaining the barrel in register with the air cylinder.

10. An air weapon according to claim 7, in which a supporting arm is provided integral with the air cylinder to which both the barrel and the cocking lever are rotatably mounted.

11. An air weapon according to claim 7, in which a supporting arm is provided integral with the air cylinder to which both the barrel and the cocking lever are rotatably mounted, and in which the cocking lever and the supporting arm are provided with co-operating projections and recesses to lock the barrel to the air cylinder in air-tight register.

12. An air weapon according to claim 7, in which a supporting arm is provided integral with the air cylinder to which both the barrel and the cocking lever are rotatably mounted, and in which the cocking lever and the supporting arm are provided with co-operating projections and recesses to lock the barrel to the air cylinder in air-tight register, and a spring is provided between the supporting arm and the barrel to move the barrel in its tilted position when released by the cocking lever.

FRANZ MÖLLER.
